BAG CLOSING DEVICE

Herman Kluger, White Plains, N. Y., assignor to
 Fulford Manufacturing Company, a corpora-
 tion of Rhode Island

Application November 16, 1938, Serial No. 240,617

3 Claims. (Cl. 150—10)

This invention relates to a closing device for a bag formed of flexible material which has a mouth opening; and has for one of its objects to provide a very simple operation for opening the bag such as by merely pulling on the opposite sides thereof and closing the bag by merely pushing on the opposite sides thereof, the arrangement being such that the bag will stay open or closed without locks or additional fastening devices.

Another object of the invention is to provide a device which will tend to move to closed position when in a position approximating its closed position and yet will, when moved to an extreme open position, remain open.

Another object of the invention is to provide a closure device for bags having a variety of shapes other than in a straight line across their mouth opening.

A further object of the invention is to provide a single resilient means which will function to hold the bag either open or closed.

With these and other objects in view, the invention consists of certain novel features of construction, as will be more fully described, and particularly pointed out in the appended claims.

In the accompanying drawings:

Fig. 1 is an elevation of a bag equipped with the improved closure device;

Fig. 2 is a top plan view of the bag;

Fig. 3 is a fragmental perspective view illustrating the bag in open position with parts about its mouth opening broken away to show the structure of the closure means;

Fig. 4 is a section on line 4—4 of Fig. 3;

Fig. 5 is a top plan view of one of the closure members in closed position;

Fig. 6 is a sectional view of the closure member in open position;

Fig. 7 is a perspective view of one of the hinge parts;

Fig. 8 is a perspective view of another of the hinge parts;

Fig. 9 is a perspective view of the end of one of the arms; and

Fig. 10 is a perspective view of a spring for biasing the hinge parts in one direction or the other; and

Fig. 11 is a fragmental side elevation of a modified form of bag;

Fig. 12 is a fragmental side elevation of a modified form of bag; and

Fig. 13 is a section on line 13—13 of Fig. 12.

In the use of bags, such for example as ladies' handbags, it is desirable to provide a bag which

is held closed without locks or similar devices and which may be opened by merely pulling on the opposite sides thereof, and which may be closed by merely pressing on the opposite sides such as pushing these opposite sides towards each other, and which will stay closed without any locks or latches; and in order to provide a bag which may function in this manner I have a device at the mouth opening of the bag, which has two arms which are hinged together with a hinge so arranged that it may be biased to cause the arms to spread apart when in open position or biased so as to cause the arms to move towards each other for a closed position; and the following is a more detailed description of the present embodiment of this invention, illustrating the preferred means by which these advantageous results may be accomplished:

With reference to the drawings, 11 designates generally the bag having a pouch material 12 with a mouth opening 13 at the upper part of the pouch material with the plane or planes of the edges of the mouth opening extending generally across the bag. Pockets formed by spaced walls 14 and 15 of the material are formed along the opposite edges of the opening 13 of the pouch material. Members designated generally 16 are arranged at least at one end of the opening, and as here shown are at each end of the openings 13. These members each consist of a pair of arms 17, 17' which are of flexible ribbon-like stock although they have some stiffness which extend along the lips of the mouth opening a major portion of the length thereof and, which are connected together by a hinge designated generally 18.

This hinge consists of a sheet metal part 19 folded at right angles as at 20 and provided with ears 21 and 21' also bent up at right angles along the sides of the sheet stock 19 and against which the right angular end 20 may rest. These ears are provided with openings 22, 22'. The other part of the hinge consists of a piece of sheet stock 23 which is rolled to form suitable eyes 24 which may be continuous across the strip or in spaced sections. These eyes align with the openings 22 in the ears 21 and a pintle pin 25 is passed through these ears and eyes and riveted over as at 26 to hold the same against endwise movement. These two sheet metal parts 19 and 23 are suitably secured to the arms 17 and 17' by rivets passing through openings 27 and 28. At the time of assembly of the sheet metal hinge part 23 with the arm 17' a spring 29 is also riveted in place by means of its openings 30 register-

ing with the openings 28. This spring extends over and engages the cam edge 31 of the end 20 of the hinge part 19 and when in the position shown in Fig. 3 so engages the spring with reference to the pivot 25 as to tend to swing the hinge parts open and spread the arms 17, 17'. However, when the hinges are swung toward each other and the end wall 20 has its cam surface 31 engaging the spring 29 at the position illustrated 10 in Fig. 5, the point of engagement of this cam with relation to the pivot is such as to tend to swing the arms 17, 17' toward each other and thus close the mouth opening of the bag, as illustrated in Fig. 2.

15 In order that the bag may be easily opened, handles 32, 32' are positioned on the opposite sides of the bag so that a pull on these handles will open the bag. In closing the bag it is merely necessary to squeeze the mouth opening, in this 20 case at each end of the mouth opening, and the mouth opening will snap to its closed position.

This arrangement of two separate members at the opposite ends of the mouth opening of the bag affords an opportunity for arranging the bag 25 as illustrated in Figs. 11 and 12 in a shape other than straight across the mouth opening. For instance, the bag designated generally 12 has the edges of its mouth opening 35 inclined in V-shape with each of the members 16 arranged at an angle 30 and spaced apart as at 36 permitting of this angular arrangement.

In Fig. 12 instead of placing the member 16 in pockets along the edge of the bag so that it will be concealed, I have arranged these members on 35 the outside of the edge of the bag opening where no pockets need be formed but merely some sort of reinforcement 37 provided. In this case the arms 17 will have prongs or spurs 38 to fasten them to the reinforcement 37. The outer surface 40 of these arms will be embellished or formed in some ornamental appearance. The hinges also will be made of an attractive shape and construction but will serve equally well to perform their desired closing or opening function.

In the forms of device illustrated in all three arrangements, as shown in Figs. 1, 11 and 12, ornaments may be secured along the edge with the arm serving to assist in holding the ornament such as a washer or backing in Figs. 1 and 11 for better supporting the ornament on the bag.

The foregoing description is directed solely towards the construction illustrated, but I desire it to be understood that I reserve the privilege of resorting to all the mechanical changes to which 55 the device is susceptible, the invention being defined and limited only by the terms of the appended claims.

I claim:

1. In a bag of flexible material having a mouth opening, a closure member comprising a hinge connected to the bag and located at one end of the mouth opening and a pair of elongated arms connected by said hinge and extending along the lips of the mouth of the bag from the hinge, the distance of the length of said arms from the hinge to their free ends being less than the length of the mouth opening, said hinge containing means 10 to yieldingly bias said arms toward each other when said arms are placed in one position to hold the bag mouth fully closed and away from each other when said arms are placed in another position, and a stop to limit the opening of said arms to hold the bag mouth open in the shape of a V in the plane of the mouth opening with the vertex of the V at the hinge end of the opening.

2. In a bag of flexible material having a mouth opening, a pair of individual and separate closure members connected to the bag and located one at each end of the mouth opening, each member comprising a pair of elongated arms and a hinge connecting said arms together at one end, said arms extending toward each other from said 20 hinge connection along the lips of the mouth opening a major portion thereof, said hinge containing means to yieldingly bias said arms toward each other when said arms are placed in one position to hold the bag mouth fully closed and 25 away from each other when said arms are placed in another position, and means to limit the opening of said arms of each member to hold the bag mouth open in the shape of a pair of opposed V's in the plane of the mouth opening.

3. In a bag of flexible material having an elongated mouth opening, four arms, hinge means connected to the bag and located at one end of the opening joining the ends of two of said arms, and hinge means connected to the bag and located at the other end of the opening joining the ends of the other two of said arms, said pairs of connected arms extending toward each other from their hinge means with the extent of the arms along the lips of said opening less than the 45 length of the opening but extending a major portion of the length of the opening, said hinge containing means to yieldingly bias said arms toward each other when said arms are placed in one position and away from each other when said arms are placed in another position whereby to hold the bag mouth fully closed or open in the shape of a pair of opposed V's in the plane of the mouth opening.

HERMAN KLUGER. 55
